UNITED STATES PATENT OFFICE.

JESSE TEMPLE CURTIS, OF BEMENT, ILLINOIS.

EXPLOSION-ENGINE.

1,165,324.

Specification of Letters Patent. Patented Dec. 21, 1915.

Application filed December 2, 1914. Serial No. 875,151.

To all whom it may concern:

Be it known that I, JESSE T. CURTIS, a citizen of the United States, residing at Bement, in the county of Piatt and State of Illinois, have invented a new and useful Explosion-Engine, of which the following is a specification.

The present invention relates to improvements in explosion engines, one object of the invention, being the provision of a four cycle engine in which a tubular piston valve interlines the cylinder of the engine and has disposed therewithin for reciprocation, the power piston, the cylinder of the engine being provided with a lower intake port and an upper exhaust port, the tubular piston being provided with a single port constituting the intake port and disposed for movement into and out of registration with the intake port of the cylinder, the upper end of the tubular piston being disposed to be moved above or below the exhaust port to thus control the same.

A further object of the present invention, is the provision of an explosion engine of this type which is simple, inexpensive and durable in construction, and which due to such simplicity is efficient and practical in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a cross sectional view through an engine constructed according to and embodying the present invention, the piston being in its lowermost position at the point of intake, and just previous to the compression stroke thereof. Figs. 2, 3, 4 and 5 are diagrammatic views illustrating the various positions of the piston and piston sleeve or valve during the respective strokes of the power piston. Fig. 6 is an additional diagram showing the relative position of the power piston and tubular piston.

Referring to the drawings, the numeral 1 designates the crank case, which carries the power cylinder 2 closed at its upper end and provided with an intake port 3 at a point

adjacent its lower end, the exhaust port 4 being disposed at a point adjacent the upper end thereof and at a point diametrically opposite to the intake port 3.

Mounted for reciprocation within the power cylinder 2 is a tubular piston 5 which is provided with a single port 6 near the lower end thereof for registration with the intake port 3 of the engine, the upper end of the piston 5 being disposed as clearly illustrated in Fig. 5 to pass below the exhaust port to uncover the same and thus permit of the passage of the exhaust gases through such port. The upper end of the piston 5 is provided with a plurality of packing rings 7, which surround the same and thus make a gas tight joint adjacent the upper end of the sleeve and the internal portion of the cylinder.

In order to provide a means for reciprocating the tubular piston 5 in consonance or in timed relation with the power piston 14, a lug 7 is formed upon the lower end thereof and projects within the crank case of the engine, a piston rod 8 being connected thereto and eccentrically to the large gear 9, which is fixed upon the counter shaft 10, this counter shaft 10 being disposed in parallel to the crank shaft 12 so that the gear 9 may mesh with the gear 11 and thus receive its motion from and impart motion to the crank shaft. By this means, the counter shaft 10 revolves one revolution every two revolutions of the crank shaft so as to reciprocate the tubular piston 5 in proper timed relation to the power piston 14.

Connected to the crank shaft is a piston rod 13, which in turn is connected to the power piston 14, said power piston 14 being mounted for reciprocation therein in the usual manner. The power piston 14 as shown is provided with a plurality of packing rings 15 adjacent the upper end thereof, so that when the same assumes the position as shown in Fig. 1, at its lowermost stroke, the gas cannot pass therebelow into the crank case as it enters into the chamber formed in the sleeve and the portion of the cylinder 2.

By constructing the tubular piston 5 as illustrated, the walls thereof are relatively thick so that the upper end constitutes a piston to assist in the propulsion, through the counter shaft, of the crank shaft as the upper end presents considerable area to receive the force of the explosion. It there-

fore follows that the tubular piston is not pulled down to effect the exhaust in the manner that a sleeve valve is operated, but is driven forward or downward by the explosion and permits the exhaust at about the bottom of its stroke, or when the exhaust port is uncovered, which in the experiments with the present engine, occurs during the final one-quarter inch of the downward stroke. While the tubular piston has made its power stroke, the power piston has made its full power stroke, the power piston reaching the limit of its stroke at the time the tubular piston begins the last quarter inch of its forward stroke. While the tubular piston makes this one-quarter inch travel and returns again, that is one-quarter inch down and one-quarter inch up, which fully opens and again closes the exhaust port, the power piston has made a complete upward stroke scavenging the engine. At this time the exhaust port is closed and the power piston is ready to start upon the suction stroke.

In order to more fully explain the operation, reference is had to Fig. 6, in which 14 designates the power piston and 5 the tubular piston, the arrows indicating the direction of travel of the crank shaft and counter shaft respectively. Therefore the travel of the power piston starting as for instance at *e* and the tubular piston starting at *a*, at the time of the explosion would have the following result: As the tubular piston only makes one-half as many strokes as the power piston, the tubular piston will travel from *a* to *b*, while the power piston travels from *e* to *f*. The power piston has now reached the limit of its power stroke and the tubular piston has arrived at the exhaust port. The power piston now travels from *f* to *e*, cleaning the cylinder of burnt gases, while the tubular piston travels from *b* to *c*, thus opening and closing the exhaust port during this interval. The power piston is now ready for the downward suction stroke, and while it travels from *e* to *f* again, the tubular piston travels from *c* to *d*, Fig. 6, which it raises a sufficient distance above the exhaust port to insure a good sealing of the compression chamber. While the tubular piston travels from *d* to *a*, the power piston travels from *f* to *e*, making the compression stroke, both pistons arriving now at the starting point and ready for the explosion.

The intake occurs about the time that the power piston reaches the limit of its suction stroke and about the time the tubular piston arrives at *d*. The intake port is closed by the power piston as it moves back on the compression stroke. During the compression stroke of the power piston, the tubular piston shaft travels from *d* to *a*, and both pistons are now ready for their forward travel under the impulse of the explosion.

The intake port of the tubular piston is so placed that when the tubular piston arrives at *b* and the power piston at *f*, the intake port will be below the head of the power piston a sufficient distance to insure that there will be no leakage into the carburetor or mixer as the case may be.

It will thus be seen that the intake opening of the cylinder may be much wider than the port in the tubular piston and its function is merely to supply the explosive mixture to the intake port in the tubular piston.

As illustrated in Figs. 2, 3, 4 and 5 the various positions of the pistons are illustrated and are readily read in conjunction with the diagram of Fig. 6.

It will thus be seen that the tubular piston has a number of advantages over the sleeve valve usually employed in engines of this type, in that it is much shorter, it having been found in practice that a 9 inch tubular piston is sufficiently long to permit of a 6 inch stroke of the power piston, thus greatly reducing the weight and permitting a shorter cylinder. With this form of tubular piston, the usual exhaust port carried thereby is dispensed with, and that by arranging as illustrated, the same following the explosion uncovers the walls of the cylinder at the hottest point of combustion permitting the heat to act directly upon the walls of the cylinder, thus keeping the tubular piston and the cylinder walls at nearly the same temperature and entirely overcoming the fault of "sleeve sticking" due to the unequal expansion and contraction of the parts. It has also been found in practice, that the present tubular piston is easily lubricated by a splash from the crank case, both the power piston and the tubular piston being sufficiently oiled from this point. It will also be noted that the principal exhaust control which happens at the end of the tubular piston, while it is making a slight movement to uncover one direction and to cover in the opposite direction, is a decided advantage over mounting the upper end of the sleeve within a jacket and carrying an exhaust port itself, it necessitating only the intake port at the opposite end of the piston and such intake port being placed in registration with the intake port of the engine and at the opposite movement of the parts from the exhaust, thus producing a perfectly balanced action at the time of intake and exhaust of the present engine.

What is claimed is:

1. A four-cycle explosion engine, including a crank case, a crank shaft, a cylinder having a sealed upper end and having its open lower end in communication with the crank case, a tubular piston mounted for reciprocation within and lining the cylinder, the upper end of the tubular piston being adapted to project above the exhaust port

to control the same and forming an auxiliary power piston, said tubular piston being provided with a port adjacent the opposite end for registration with the intake port of the cylinder, a power piston operably connected to the crank shaft, and means connecting the tubular piston to the crank shaft, whereby the tubular piston during reciprocation begins the uncovering of the exhaust port at 10 the extreme lowermost point of the explosive stroke of the power piston, and upon the beginning of the up-stroke thereof, and also assists in moving the crank shaft during the explosive stroke.

15 2. A four-cycle explosion engine, including a crank case, a crank shaft, a cylinder having a sealed upper end and having its lower end in communication with the crank case, a tubular piston mounted for reciprocation 20 within and lining the cylinder, the upper end of the tubular piston being relatively thick and forming an auxiliary power piston and being adapted to project above the ex-

haust port to control the same, said tubular piston being provided with a port adjacent 25 the opposite end for registration with the intake port of the cylinder, a power piston operably connected to the crank shaft, means connecting the tubular piston to the crank shaft, whereby the tubular piston is reciprocated to begin the uncovering of the exhaust port at practically the extreme lowermost point of the explosive stroke of the power piston and upon the beginning of the up-stroke thereof, the power piston coöperating 30 with the intake port of the sleeve to control the intake port and both pistons coöperating during the explosion to operate the crank shaft.

In testimony that I claim the foregoing as 40 my own, I have hereto affixed my signature in the presence of two witnesses.
